UNITED STATES PATENT OFFICE.

MARK A. BROWN, OF CHATTANOOGA, TENNESSEE.

CAR-COUPING.

1,146,233.

Specification of Letters Patent. Patented July 13, 1915.

Continuation of application Serial No. 785,430, filed August 18, 1913. This application filed November 10, 1913. Serial No. 800,193.

To all whom it may concern:

Be it known that I, MARK A. BROWN, a citizen of the United States, residing at Chattanooga, in the county of Hamilton and State of Tennessee, have invented a new and useful Car-Coupling, of which the following is a specification.

The invention relates to improvements in car couplings, and is a continuation of an application filed by me Aug. 18, 1913, Serial No. 785,430.

The object of the present invention is to improve the construction of car couplings, more especially the draw bar and the means for mounting the same, and to provide a simple, efficient and comparatively inexpensive ball bearing car coupling, adapted to be readily shifted in a direction laterally of the car by the operating means of the car coupling to arrange it in proper position for automatic coupling, and capable, when free to move, of automatically returning to a central position.

With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing:—Figure 1 is a plan view partly in section of a car coupling, constructed in accordance with this invention. Fig. 2 is a side elevation of the same, partly in section. Fig. 3 is a transverse sectional view on the line 3—3 of Fig. 2. Fig. 4 is a detail perspective view of the ball bearing plate.

Like numerals of reference designate corresponding parts in all the figures of the drawing.

In the accompanying drawing in which is illustrated the preferred embodiment of the invention, 1 designates a draw head provided with a draw bar 2 having an oppositely inclined bottom face 3, extending downwardly and inwardly from the side face of the draw bar to the center thereof and arranged upon a seat formed by a ball bearing plate 4, mounted within a carrier iron 5. The carrier iron 5, which is suitably

secured to the framework of the car, is preferably composed of spaced vertical sides and a straight transversely disposed bottom connecting portion 6, as clearly illustrated in Fig. 3 of the drawing. The ball bearing plate, which has a flat horizontal face 7, is fitted against the upper face of the bottom connecting portion 6 of the carrier iron, and it extends entirely across the same and is provided at its side edges with depending flanges 8, fitting against the side edges of the said bottom connecting portion 6 of the carrier iron and forming a bottom recess to receive the said bottom portion 6, whereby the ball bearing plate is detachably interlocked with the carrier iron. The ball bearing plate is maintained firmly in interlocked relation with the carrier iron by the weight of the car coupling, it being unnecessary to provide any fastening means for securing the bearing plate to the carrier iron.

The upper face 9 of the ball bearing plate is oppositely inclined in a longitudinal direction to conform to the configuration of the oppositely inclined bottom face 3 of the draw bar 2, and the said upper face 9 inclining downwardly and inwardly from the ends of the bearing plate to the center thereof. The oppositely inclined portions of the upper face 9 of the bearing plate are rounded transversely of the bearing plate and extend downwardly from the longitudinal center to the side edges thereof to prevent frictional contact of the shank of the car coupling with the bearing plate should one end of the car coupling drop to a lower position than the other. By this construction, the upper face of the ball bearing plate is oppositely inclined both longitudinally and transversely. The ball bearing plate is provided in its upper face with a central longitudinal ball receiving groove 10 of substantially cylindrical form extending throughout the entire length of the bearing plate and receiving a plurality of antifriction balls 11, the series of balls being preferably of a length in excess of the width of the shank 2 of the car coupling, as clearly illustrated in Fig. 3 of the drawings.

The ball receiving groove 10 partially embraces the major portion of the anti-friction balls, which project slightly above the upper face of the bearing plate to form a rolling ball bearing support for the draw bar 2. The antifriction balls 11 are retained in the

groove 10 by the oppositely curved partially overhanging walls thereof and also by the sides of the carrier iron, which close the ends of the groove when the parts are assembled. The series of antifriction balls are oppositely inclined and are adapted to center the car coupling, and they enable the same to be easily shifted by a transverse knuckle unlocking shaft 12, or any other suitable means for arranging the car coupling in proper position for automatic coupling. As the operating shaft is mounted on the car coupling for rotary movement to lock and release the knuckle and has no longitudinal movement relative to the car coupling, it is adapted to shift the latter in either direction without affecting the operation of the locking mechanism. Also the ball bearing support for the car coupling permits the latter to move frictionlessly in the lateral swaying incident to the motion of the train. The opposite inclination of the groove 10 is also adapted to retain the balls centrally of the bearing plate in handling the latter, so that there is little liability of the balls accidentally dropping out of the groove when placing the bearing plate within the carrier iron or removing it therefrom.

The ball bearing plate and the transverse connecting portion 6 of the carrier iron are provided with registering slots or openings 13 and 14, forming an outlet for cinders and other accumulation and preferably flared at the bottom, as illustrated in Fig. 2 of the drawing. Any cinders or dust dropping into the groove will be worked through the outlet opening and discharged from the ball bearing seat of the car coupling by the action of the balls.

What is claimed is:

1. A car coupling including a carrier iron having spaced sides and a connecting portion, a seat arranged upon the connecting portion of the carrier iron and provided with means for detachably interlocking it with the said iron, said seat being provided in its upper face with a groove extending the entire length of the seat and closed at its ends by the sides of the carrier iron, a draw bar, and a series of antifriction balls arranged in the groove and supporting the draw bar, the walls of the groove partially embracing the major portion of the antifriction balls, whereby the latter are retained in the groove.

2. A car coupling including a carrier iron having spaced sides and a connecting portion, a draw bar provided with an oppositely inclined bottom face, a seat arranged upon the connecting portion of the carrier

iron and provided with an oppositely inclined upper face having a longitudinal groove extending the entire length of the seat and closed at its ends by the sides of the carrier iron, said groove being composed of oppositely inclined portions, and anti-friction devices arranged in the groove and supporting the draw bar and adapted to center the same. 70

3. A car coupling including a draw bar provided with an oppositely inclined bottom face, a seat having an oppositely inclined face and provided therein with a groove composed of inclined portions and disposed transversely with relation to the draw bar, a series of antifriction balls arranged in the said groove and supporting the draw bar and adapted to center the same, the walls of the groove partially embracing the major portion of the anti-friction balls, whereby the latter are retained in the said groove, and means for closing the ends of the groove, the latter being of sufficient length to permit the balls to roll transversely of the draw bar. 80

4. A car coupling including a carrier iron composed of spaced sides and a connecting bottom portion, a bearing plate fitted in the carrier iron and provided with an oppositely inclined upper face and having a groove extending along the bearing plate entirely across the carrier iron, the ends of the groove being closed by the side portions of the said carrier iron, antifriction devices confined in the groove by the walls thereof and projecting above the upper face of the bearing plate, and a car coupling having a draw bar provided with an oppositely inclined bottom face supported by the said antifriction devices and automatically centered by the same. 90

5. A car coupling including a draw bar provided with an oppositely inclined bottom face extending downwardly and inwardly from the sides of the draw bar to the center thereof, a seat having an oppositely inclined upper face extending upwardly and outwardly from the center of the seat to the ends thereof, the upper face of the said seat being also inclined laterally from the center to the side edges, and anti-friction devices mounted on the seat at the center thereof and supporting the draw bar. 105

In testimony, that I claim the foregoing as my own, I have hereto affixed my signature in the presence of two witnesses.

MARK A. BROWN.
